UNITED STATES PATENT OFFICE

WALDEMAR KOPS, OF NEW YORK, N. Y., ASSIGNOR TO KOPS BROS. INC., OF NEW YORK,
N. Y., A CORPORATION OF NEW YORK

APPAREL GARMENT

Application filed August 19, 1929. Serial No. 386,828.

This invention relates to an apparel garment of the girdle type which is so constructed and made of such material as to be adapted to fit the body and to be maintained in position thereon without the employment of the usual hose supporter straps to prevent the same from creeping upwardly. The garment is of the same general type as that disclosed in Letters Patent No. 1,636,516 granted to me July 19th, 1927. The garment of the patent, however, includes buttocks straps, together with a crotch strap, the latter being adjustable longitudinally of the garment to accomplish the intended purposes and in which the crotch strap, due to the manner in which it is adjustable in the garment, bears against the crotch of the wearer with varying degrees of pressure. Now the garment made in accordance with the present invention also includes a crotch strap, but the buttocks straps are entirely dispensed with. The crotch strap, furthermore, is made adjustable to position and is so associated with the lower portions of the garment that these parts of the girdle surround and yieldingly engage the upper parts of the limbs of the wearer, whereby the necessary pressure is placed on the limbs of the wearer to maintain the garment in position without necessarily causing the crotch strap to exert any pressure whatsoever against the body of the wearer. The garment, furthermore, is made of a suitable material which is yieldable to a greater extent in one direction than in the other and the material is so cut and placed in the garment that with the exception of the front member the parts of the garment are yieldable longitudinally therein, causing the same to conform to and properly fit over the thighs and buttocks of the wearer, as will be hereinafter more particularly described.

In the drawings Figure 1 is a perspective view illustrating the garment made in accordance with my invention,

Fig. 2 is an elevation of the front of the garment,

Fig. 3 is an elevation of the rear of the garment,

Fig. 4 is a section on line 4—4, Fig. 2,

Fig. 5 is a section on line 5—5, Fig. 2, and

Fig. 6 is a diagrammatic plan of the manner in which the fabric of which the garment is made may be knitted or otherwise constructed.

Referring to the drawings the garment includes a front member 10 which, like all the other members of the garment, is a two ply structure. The outer ply of this member is indicated at 11 and the inner ply at 12. The front member 10 is preferably wider at the top than at the bottom with the side portions converging downwardly, as clearly indicated in Fig. 2. In this front member there is a liner 13 between the inner and outer plies thereof.

The garment also includes side members 14 and 15, together with a back member 16. As hereinbefore stated, these members, that is, the side members and the back member, are also preferably constructed to include an outer and an inner ply. The front member 10 is connected to the right hand side member 14 by suitable lines of stitching 17 and the opposite side of the front member is connected to the left hand side member 15 by a suitable line of stitching 18, or otherwise. The rear edge of the right hand side member 14 is connected to the adjacent edge of the back member 16 by a line of stitching 19, or otherwise. Similarly the rear edge of the left hand side member 15 is connected to the adjacent edge of the back member 16 by a suitable line of stitching 20, or otherwise.

The upper portion of the division line between the front member 10 and the left hand member 15 is preferably open and the edges thereof fitted with reinforcing strips 21 and 22. The reinforcing strip 21 is provided with spaced hooks 23 and in corresponding posi-

tions the reinforcing strip 22 is provided with eyes 24, the hooks 23 being adapted to engage the eyes 24 to form a convenient type of closure for the upper portion of the garment.

5 The back member 16 is provided with a liner indicated at 25 and located between the inner and outer plies thereof. This liner member is of appreciable width and extends entirely across the lower edge portion of the 10 back member. In suitable positions in the lower part of the back member and extending through the plies thereof and also through the liner member 25 there are sets of eyelets indicated at 26 and 27, the eyelets 15 26 being on the right hand side of the garment and the eyelets 27 on the left hand side thereof.

The garment also includes a crotch strap 28. This may be of any desired configuration 20 and is also preferably made of two plies of material. As indicated in Fig. 5 one ply is designated at 29 and the other at 30. Between the inner and outer plies of the crotch strap member there is a liner 31.

25 One end of the crotch member 28 is connected to the lower end of the front member 10 by a line of stitching 32 or otherwise and this end of the crotch member, as illustrated, is preferably coextensive circumferentially 30 with the lower end of the front member. At its opposite end the crotch member is fitted with diverging straps 33 and 34 which are preferably made of elastic material and at the free extremities of these straps 33 and 35 34 there are hooks 35 and 36, the hooks 35 and 36 being adapted respectively to engage in either one of the sets of eyelets 26 and 27 arranged, as hereinbefore described, circumferentially along the lower edge of the back 40 member 16.

Because of the use of the liner member 13 in the front member of the garment this front member is substantially unyielding. The other members of the garment, however, are 45 made of a material such, for example, as glovesilk material, or the like, which is so knitted, as indicated diagrammatically in Fig. 6, or otherwise, as to be stretchable or yieldable to an appreciable extent in one direction, whereas in the other direction the fabric is substantially unyielding. The side members, as well as the back member of the garment, are made of such a material and the material is so cut and the garment made 55 up that the parts thereof, that is, the side members and the back member, are longitudinally stretchable or yieldable in order to readily conform to the body of the wearer, fitting smoothly over the thighs and buttocks.

60 In the use of the garment the hooks 35 and 36 are caused to engage in any one of the sets of eyelets 26 and 27 and an adjustment effected around the upper portions of the limbs of the wearer so as to cause the 65 same to be engaged with any desired tension

by these parts of the crotch strap and the intermediate lower portions of the garment, that is, the lower forward parts of the back member and the lower edge portions of the side members. In this manner these parts 70 of the garment may be made to adjustably engage the upper parts of the limbs of the wearer in order to maintain the garment in the desired position on the body and to effect this purpose without causing the crotch member 75 to exert any pressure against the body, or, for that matter, to come into contact with the body at all.

It will be understood that the structure of the garment is not precisely limited to that hereinbefore described as, for example, the closure may be placed in any desired position or entirely omitted in some instances, and also the material may be varied without departing from the nature and spirit of the 85 invention.

I claim as my invention:

1. In a garment of the type described, a girdle adapted to extend around the abdominal portion of the body of a wearer, a crotch member extending from the lower front edge 90 of the girdle, and means for connecting the crotch member in any one of a plurality of positions along the lower edge portion of the back of the girdle to cause the crotch member 95 and the lower edge portions of the girdle to engage the upper parts of the limbs of the wearer to maintain the girdle in position on the body.

2. In a garment of the type described, a girdle adapted to extend around the abdominal portion of the body of a wearer, a crotch member extending from the lower front edge portion of the girdle, and means for adjustably connecting the crotch member in any one 100 of a number of sets of eyelets all arranged circumferentially in a single row in the lower portion of the girdle at the back thereof to cause the crotch member and the lower edge 105 portions of the girdle to engage the upper parts of the limbs of the wearer to maintain the girdle in position on the body.

3. In a garment of the type described, a girdle comprising a front member, side members and a back member adapted to surround the abdominal portion of the body of a wearer, a plurality of eyelets arranged circumferentially in the lower edge portion of the back member, a crotch member connected at one end to the lower edge portion of the front member, and means extending from the other end of the crotch member and adapted to yieldingly connect with any set of said eyelets to cause the said crotch member and the lower edge portions of the girdle to engage 120 the upper parts of the limbs of the wearer to maintain the girdle in position on the body.

4. In a garment of the type described, a girdle comprising an unyielding front member, side members and a back member, the 125

said side and back members being made of a material yieldable in one direction and so placed in the garment that the material is yieldable longitudinally thereof, permitting the side and back members to fit over and conform to the thighs and buttocks of a wearer, and means connected between the front and back members for yieldingly engaging the upper parts of the limbs of the wearer to maintain the garment in position on the body.

Signed by me this 8th day of August, 1929.
WALDEMAR KOPS.
